UNITED STATES PATENT OFFICE.

JOSEPH C. DONNELLY, OF BARBERTON, OHIO, ASSIGNOR TO THE DIAMOND MATCH COMPANY, OF CHICAGO, ILLINOIS, A CORPORATION OF ILLINOIS.

MACHINE FOR PACKING MATCH-BOOKS, &c.

1,280,685.

Specification of Letters Patent.

Patented Oct. 8, 1918.

Application filed November 4, 1916. Serial No. 129,451.

To all whom it may concern:

Be it known that I, JOSEPH C. DONNELLY, a citizen of the United States, and resident of Barberton, in the county of Summit and State of Ohio, have invented certain new and useful Improvements in Machines for Packing Match-Books, &c., of which the following is a specification.

This invention relates to machines for packing match-books and the like; having reference, more especially, to certain improvements in the packing machine set out in Letters Patent of the United States No. 1,132,309, dated March 16, 1915.

In the particular form of machine illustrated in said patent rows of match books, with the larger ends of alternate books reversed, are ejected successively from a carrier to an underlying bed and are thereon longitudinally compressed by the opposing action of plungers against the respective ends of each row. Each row of books thus compressed, or each pair of adjacent rows with or without a partition strip between them, is moved upon and supported by spring-closed gear-connected shutters overhanging the open upper end of a chute containing a box or carton, and the row or rows of books is or are then bodily depressed by the downward stroke of a vertically-reciprocating plunger, whereby the shutters are forcibly opened against the action of their spring-closing connection and the books thus entered into the box or carton. During the upward or return stroke of the plunger the shutters resume their normal or closing position for the support of a succeeding row or rows of match books preparatory to their delivery to the same or to another box.

An object of the present invention is to provide for the positive opening and closing of the shutters in timely relation to the travel of the delivery plunger whereby the otherwise liability of subjecting the match books to crushing pressure by said plunger is obviated.

Another object is to insure the accurate guidance of the books into the underlying box or carton.

A further object is to provide for the packing of the match-books in boxes or cartons of different sizes.

With these and other objects in view my invention comprises various features of construction and combinations of parts which will be hereinafter described and claimed.

In the drawings—

Figure 1 is a longitudinal vertical section, partly in elevation, of a portion of a match-book packing machine embodying a preferred form of my invention.

Fig. 2 is a transverse vertical section of the machine, as on the line 2—2 of Fig. 1.

Fig. 3 is a partial transverse vertical section through the book compressing mechanism and adjuncts, as on the line 3—3 of Fig. 1.

Fig. 4 is a perspective view of the positively-operated shutter mechanism and parts associated therewith.

Fig. 5 is a longitudinal vertical section through the shutter mechanism, as on the line 5—5 of Fig. 2.

Fig. 6 is a similar view, enlarged, showing the shutters in open position.

Fig. 7 is a transverse vertical section, as on the line 7—7 of Fig. 6.

Referring to the drawings, 10 designates a part of an intermittently movable carrier comprising an endless chain of links having a succession of spaced blades which support a column of match books with the larger ends of alternate books reversed.

11 designates a vertically-reciprocating plunger head by means of which succeeding rows of match books are periodically ejected from the carrier and deposited upon an underlying bed 12. In the present instance this plunger head is carried by an oscillatory arm 13 borne by a suitably-supported rock shaft 14. On the shaft is a crank-arm 15 which is connected by means of a link 16 with a rock-arm 17 pivoted on a bracket 18 depending from the bed-plate; the pin joint of the link and arm bearing a roller 19 which travels in the cam race 20 of a cam 21 on a driven shaft 22 of the packing machine, and the contour of the cam race being such as to effect through the connections described the rapid reciprocation of the plunger head at a predetermined interval in the rotation of the cam.

23, 24 designate two horizontally-reciprocating plunger heads positioned and operated to act in opposition to each other.

against the respective ends of each row of books deposited upon the bed 12, and thus compress the row sufficiently to insure its easy entry into a suitably-disposed box or 5 carton, as 25. In the present illustration the plunger head 24 is formed with an outwardly extending member 26 perforated for the reception of the upper end of a vertical rock-arm 27 which, extending through 10 a slot in the bed, is pivoted at its lower end to a suitably-disposed bracket 28 on the base 29 of the supporting frame of the packing machine. Pivoted to this arm, near its upper end, is one extremity of a horizontal 15 bar 30 which extends beneath and transversely of the bed and is slidingly fitted in the ways of a suitably-disposed guide 31. The bar 30 has formed thereon a gear rack 37 which meshes with a pinion 38 on a 20 short shaft 39 having its bearings in brackets 40 on the bed, which shaft also bears a pinion 41 in mesh with rack-teeth formed on a slide member 42 carrying the plunger-head 23. On the shaft 22 is a cam 43, 25 the race of which receives a roller 44 on the rock-arm 27, and thereby effects the timely oscillation of the latter. This rock-arm thus horizontally reciprocates the adjacent plunger head 24 and through the rack and gear 30 connections, also actuates the head 23 simultaneously with but reversely of its companion.

45 designates a horizontal plunger head movable at right angles to the end plunger 35 heads and positioned to act against the opposing side of the row of compressed books and push the row bodily to and upon a pair of shutters 46 which normally close a discharge throat opening in the bed, as will 40 presently appear.

The plunger head 45 is mounted to slide in ways on the bed 12 and is connected by means of a link 47 with a vertical rock-arm 48 which is pivoted at its lower end on a 45 suitably-disposed bracket 49 on the base. This arm 48 is provided with a roller 50 which runs in the race 51 of a cam 52 on a power driven shaft 53 of the packing machine, said race being formed to effect the 50 requisite oscillation of the arm and, perforce, the reciprocation of the plunger head 45. The shafts 53 and 22 are geared together to turn in the same direction, as will hereinafter appear.

55 54 designates a back stop for the row or rows of books positioned on the shutters.

55 designates a vertically-reciprocable plunger head arranged and operated to bear upon the top of the row or rows of match- 60 books above the throat in the bed when the shutters are opened as below described, and thus push the books into an underlying container. The head 55 is guided in a suitable standard 56 on the bed and is provided with

an upright extension 57 which is connected 65 by means of depending links 58 with a rock-frame 59. The lower ends of these links are united by a tie-rod 60 which affords a pivotal connection for the arms of the rock-frame. This frame is carried by a suitably-disposed shaft 61 having its bearings in 70 brackets 62 on the base. Extending from the shaft 61 is an arm 63 bearing a roller 64 which runs in the race 65 of a cam 66 on the shaft 53, and is thereby actuated in a 75 manner to effect through the connections described the timely reciprocation of the plunger head 55.

67 designates a vertical chute which is 80 arranged directly beneath the throat in the bed and is adapted to support the box or carton in position for the reception of the row or rows of match books depressed by the plunger head 55 as above mentioned. This chute, in the form illustrated, comprises a casing substantially rectangular in cross-section, open at top and bottom, and provided on one side, at its upper portion, with an inlet 68 through which empty boxes are successively delivered to the chute by 85 means of a horizontally reciprocating plunger head 69. A plunger head 70 horizontally reciprocative at right angles to the head 69 pushes the succeeding boxes from the upper run of a delivery belt 71 into the 90 path of the head 69. The belt passes about a pulley 72 suitably supported beneath the bed. The plunger heads 69, 70 may be relatively actuated in any suitable manner.

In the present instance the plunger head 100 69 is slidingly fitted to guides in a supporting frame 73 beneath the bed and is provided with a gear rack 74 with which meshes a gear wheel 75 on a shaft 76 having its bearings in brackets 77 on the under side 105 of the frame 73. On this shaft is a pinion 78 with which meshes a vertically reciprocative gear rack 79 carried by the upper end of a vertically-reciprocating bar 80. (See Figs. 1 and 3.) This bar is bifurcated at its 110 lower end to embrace the shaft 53 and is thereby vertically guided. It is also provided with a roller 81 that runs in the race 82 of a cam 83 on said shaft; the contour of the race being such as to effect the timely 115 reciprocation of the bar and the actuation of the plunger-head 69 through the intermediate gearing described.

The plunger head 70 is slidingly fitted to guides on the frame 73, at right angles to 120 the path of the head 69, so as to be movable across the upper run of the delivery belt. The head 70 is provided with a perforated rearward portion through which extends the upper end of a vertical rock arm 84 which is 125 pivoted at its lower end on a bracket 85 on the base of the supporting frame. This rock-arm 84 bears a roller 86 which runs in

the race 87 of a cam 88 on the shaft 53; said race being appropriately shaped to effect the timely operation of the rock-arm and the reciprocation of the plunger-head 70.

5 The mechanisms above generally described mainly differ in features of detail and design from the mechanisms performing corresponding functions in the machine set out in the patent aforesaid. The specific 10 structural details herein illustrated are, therefore, not of the essence of the present invention, which, as above indicated, particularly concerns the shutter mechanism of the discharge throat and the parts correlated therewith as will now be described.

The discharge throat is formed in a member 46' which is detachably seated in an appropriate opening in the bed 12, and the shutters 46 comprise plates hinged to the respective side walls of the discharge opening by means of trunnions or pintles 89. The trunnions at one end of the shutters are provided with meshing sector gears 90 which insure simultaneous uniform movement of the shutters when one or the other is swung on its axis. Parallel guide-walls 91 for a row or rows of books are supported on the frame member 46', at the respective ends of the discharge throat, and these walls preferably support on their inner surfaces guide members for the ends of the shutters. Each of these members comprises a plate having two reversely curved inwardly beveled edges 92 which are described from the respective axes of the shutters. Each of the shutters has formed on or affixed to its ends quadrant wings 93 the curved edges of which are beveled correspondingly to the adjacent edges of the proximate guide plates and are 40 slidingly fitted thereto. Thus the shutters are effectually guided and steadied throughout their swinging movements. The end wings, in conjunction with the bodies of the shutters, provide a funnel-like structure to 45 facilitate the entrance of the books into the underlying container when the shutters are swung downward, as will presently appear.

By the construction above described it is to be noted that the throat member and the 50 parts mounted thereon can be bodily applied to or removed from the bed, in order that members having throats of different sizes may be employed in accordance with the capacity of the boxes or cartons to be filled, 55 as will be later explained.

Fast on the projecting end of the trunnion of one of the shutters is a pinion 94 with which meshes a vertically-reciprocatative gear rack 95 formed on or affixed to the upper 60 portion of a depending bar 96 which is slidingly fitted to a vertical guide 97 in the bed. (See Figs. 2 and 7.)

The lower end of the bar 96 is loosely connected to one arm of a rock-lever 98 which

has its fulcrum on a suitably-disposed stud-shaft 99, the other arm of the lever being provided with a roller 100 in the race 101 of a face cam 102 on the shaft 53. The contour of the cam is such as to effect the periodic oscillation of the lever 98 and corresponding reciprocation of the pack-bar, which bar in its upstroke rotates the pinion 94 in a direction which effects the positive downward swinging of the shutters, and in its downstroke oppositely rotates the pinion to effect the positive return of the shutters to their horizontal closing position; the cam insuring the requisite dwell of the shutters in their opening and closing positions in harmony with the reciprocations of the delivery plunger. In other words, the shutters are maintained in closing position until the books are disposed thereon, whereupon the shutters are positively opened to permit the delivery of the books to the underlying box by the descending plunger 55. The shutters are maintained in open position until the delivery plunger in its upward travel clears the throat, whereupon the shutters are positively closed.

When the shutters are in open position their lower ends depend into the underlying box 25, at its respective sides, and thus constitute in conjunction with the quadrant end wings a funnel-like structure which facilitates the entrance of the books into the box, as above mentioned. (See Figs. 6 and 7.)

In order to insure the entrance of the ends of the shutters into the box and thus obviate any liability of crushing or mutilating the ends of the latter, I provide the throat with vibratory end members 103, 104 which serve as efficient guides for the downwardly swinging ends of the shutters. These members comprise relatively thin metal plates which are pivoted on brackets 105 at the respective ends of the throat member so as to be movable through vertical arcs into and from the top of a box positioned in the chute.

The member 103 depends adjacent the box-inlet 68 of the chute and below the top of the box in its passage thereto, whereby the leading end of the box, as it is entered into the chute by the plunger 69, swings the member upward and clears the same, which member then gravitates to its normal position and bears against the opposite inner end wall of the box when the box is fully within the chute, as illustrated in Fig. 6. The member 104 is similar in form and size to the member 103, but it is maintained normally above the horizontal path of the box by the action of a spring 106 which is secured to a tail-piece 107 on the member 104 and to a bracket 108 depending from the member 46'. Hence when the box is positioned within the chute with the end member 108 extending into the box, the other

4
end member 104 lies somewhat above the box, as shown in Fig. 5.

The shutters in their downward movement depress the opposing member 104 against the action of the spring into close relation with the adjacent end wall of the box as indicated in Fig. 6.

It is to be noted that the downstroke of the delivery plunger 55 is sufficient not only to enter the books into the box, but also to push the filled box downward within the chute to afford a space for the reception of the next succeeding empty box. Thus the boxes as rapidly as they are filled are depressed in the chute, and thence successively discharged through the open lower end of the chute upon an off-bearing belt 109, or the like.

The machine is herein illustrated as adapted to the packing of two rows of match books in a box or carton; the throat member and shutter mechanism being of appropriate form and size. Provision is made, however, whereby single rows of books may be packed in smaller size boxes or cartons, if desired, in which case, of course, a member having a smaller throat and associated shutters is applied to the opening in the bed.

In double-row filling the speed of the primary shaft 22 is twice that of the secondary shaft 53 in order that the timely reciprocations of the positioning plunger 45 and the delivery plunger 55, in relation to the operations of the book ejecting, compressing and shutter-actuating mechanisms (which are controlled through the cam connections on the shaft 53,) can be effected so as to position two rows of books upon the shutters and enter them in the underlying box; but in single-row filling the two shafts travel at the same speed in order that the said plungers 45 and 55 shall timely reciprocate to position a single row of books upon the shutters and enter the row of books in the underlying box. The means herein illustrated for actuating the two shafts at the required relative speeds is as follows, reference being had to Figs. 1, 2 and 3.

On the primary shaft 22 is a gear wheel 110 in mesh with an idler gear 111 borne by a stud shaft 112 having its bearings in a bracket 113 depending from the bed 12, which idler, in turn, meshes with a gear wheel 114 loose on the shaft 53, said latter shaft being provided with a clutch member 115 for coaction with a complementary clutch member 116 on the gear wheel 114, whereby said latter wheel may be rendered fast or loose on the shaft 53 as desired. The ratio of the gearing just described is such that when the wheel 114 is clutched to the shaft 53 said shaft is appropriately driven from the primary shaft for double-row filling. Loose on the primary shaft is a gear wheel

117 in mesh with an idler 118 borne by a stud shaft 119 having its bearing in a bracket 120 on the supporting frame of the machine, which idler, in turn, meshes with a gear wheel 121 fast on the shaft 53, the primary shaft being equipped with a clutch 122 which can be actuated to render the wheel 117 fast or loose on its shaft as desired.

During double-row filling the wheel 117 is loose on the primary shaft, and the wheel 114 is clutched on the secondary shaft as shown, and hence the latter shaft is driven through the medium of the gears 110, 111, 114; but when the gear wheel 114 is unclutched on the secondary shaft and the gear wheel 117 is clutched on the primary shaft, the secondary shaft, by virtue of the ratio of the gearing 117, 118, 121, is appropriately driven for single-row filling.

It is to be noted that the term "shutters" is used herein in a sense to comprehend any appropriate form of movable barrier for the discharge throat. Furthermore that the mechanisms above set forth may be varied within the principle of the invention and the scope of the appended claims. 90

I claim—

1. In a machine of the class described, the combination with a support having a discharge throat therein, of movable shutters for said throat, positive operating means for moving said shutters to and temporarily-locking them in open and closed positions, and means for feeding articles upon the closed shutters. 95

2. In a machine of the class described, the combination with a support having a discharge throat therein, of movable shutters for said throat, positive operating means for moving said shutters to and temporarily-locking them in open and closed positions, means for feeding articles upon the closed shutters, and discharge means for discharging said articles through the throat when the shutters are open. 105

3. In a machine of the class described, the combination with a support having a discharge throat therein, of shutters hinged to swing within said opening, connections whereby said shutters move as a unit, positive operating means for swinging said shutters to and temporarily locking them in open and closed positions, means for feeding articles upon the closed shutters, and means for discharging said articles through the throat when the shutters are open. 115 120

4. In a machine of the class described, the combination with a support having a discharge throat therein, of shutters hinged to swing within said opening, connections whereby said shutters move as a unit, positive operating means for swinging the shutters downward to open the throat and for returning them to closing position, said 125

- means temporarily locking the shutters in the respective positions, means for feeding articles upon the closed shutters, means for supporting a container beneath the throat, and means for discharging said articles through the throat and into the container when the shutters are swung downward. 5
5. In a machine of the class described, the combination with a support having a discharge throat therein, of shutters hinged to swing within said opening, connections whereby said shutters move as a unit, cam-actuated means for positively swinging the shutters downward to open the throat and 10 for returning them to closing position, means for feeding articles upon the closed shutters, means for supporting a container beneath the throat, and cam-actuated means for discharging said articles through the throat and 15 into the container when the shutters are swung downward. 20
6. In a machine of the class described, the combination with a support having a discharge throat therein, of shutters hinged to swing within said opening, connections whereby said shutters move as a unit, a pinion on the hinge of one of said shutters, a rack-bar in mesh with the pinion, means for reciprocating the rack and thus positively 25 swinging the shutters downward to open the throat and then upward to closing position, means for feeding articles upon the closed shutters, means for supporting a container beneath the throat, and means for dis- 30 charging said articles through the throat and into the container when the shutters are swung downward. 35
7. In a machine of the class described, the combination with a support having a discharge throat, of hinged shutters movable to open and close said throat, said shutters having end wings, means for feeding articles upon the closed shutters, means for supporting a container beneath the throat 40 in position to receive the free ends of the shutters and the adjacent portions of the end wings when the shutters are in open position, and means for discharging articles through the open throat into the container. 45
- 50 8. In a machine of the class described, the combination with a support having a discharge throat, of hinged shutters movable to open and close said throat, said shutters having end wings, guide members for said wings, means for feeding articles upon the closed shutters, means for supporting a container beneath the throat in position to receive the free ends of the shutters and the adjacent portions of the end wings when 55 the shutters are in open position, and means for discharging articles through the open throat into the container. 60
- 65 9. In a machine of the class described, the combination with a support having a discharge opening, of hinged shutters movable to open and close said throat, said shutters each having end wings, means for feeding articles upon the closed shutters, means for supporting a container beneath the throat in position to receive the free ends 70 of the shutters and the adjacent portions of the end wings, vibratory guide members at the respective ends of the throat adapted to depend into said container and means for discharging articles through the open throat 75 into the container. 80
10. In a machine of the class described, the combination with a support having a discharge opening, of a chute beneath said opening, means for feeding containers successively into the chute, normally closed shutters pivoted at the respective sides of the opening and movable downward into close relation with the inner sides of a container within the chute, two pivoted guide 85 members at the respective ends of the said opening movable into close relation with the respective ends of the container, means for feeding articles upon the closed shutters, and means for discharging said articles through 90 the throat and into the container when the shutters are swung downward. 95
11. In a machine of the class described, the combination with a support having a discharge opening, of a pivoted loosely depending guide member at one end of the opening, a pivoted guide member at the opposite end of the opening, means for maintaining the latter member yieldingly raised, and means for feeding beneath said opening 100 a container whose end walls project above the lower end of the depending member. 105
12. In a machine of the class described, the combination with a support having a discharge throat therein, a pivoted loosely depending guide member at one end of the opening, a pivoted guide member at the opposite end of the opening, means for maintaining the latter member yieldingly raised, means for feeding beneath said opening a 110 container whose end walls project above the lower end of the depending member, shutters pivoted at the respective sides of the throat, means for swinging the shutters downward against the inner sides of the container and 115 for returning them to closing position, means for feeding articles upon the closed shutters, and means for forcing said articles through the throat and into the container, when the shutters are swung downward. 120
13. In a machine of the class described, the combination with a supporting structure, of a throat member detachably mounted thereon, movable shutters for the throat of said member, positive operating means for moving said shutters to open and close the same and to lock them temporarily in their respective positions, means for posi- 125

tioning articles upon the closed shutters, and means for discharging the articles through the open throat.

14. In a machine of the class described, the combination with a support having a discharge throat, of movable shutters for said throat, means for actuating said shutters, vibratory guide means at the ends of the throat, means for positioning articles on the closed shutters, means for supporting a container beneath the throat in position to receive the free ends of the open shutters and the adjacent portions of the end guides, and means for discharging articles through the open throat into the container.

15. In a machine of the class described, the combination with a supporting structure, of a throat member detachably mounted thereon, movable shutters for the throat of said member, means for actuating said shutters, vibratory guide members at the ends of the throat, means for positioning articles upon the closed shutters, means for supporting a container beneath the throat member in position to receive the free ends of the open shutters and the adjacent portions of the end guides, and means for discharging articles through the open throat into the container.

16. In a machine of the class described, the combination with an article carrier, of means for ejecting successive rows of articles therefrom, a support upon which the articles are ejected, means for positioning one or more rows at a discharge station, means for discharging the articles thus positioned, and variable speed means for determining the operations of the positioning and discharging means in relation to the operation of the said ejecting means.

17. In a machine of the class described, the combination with an article carrier, of means for ejecting successive rows of articles therefrom, a support upon which the articles are ejected, means for compressing one or more rows thus ejected, means for positioning the compressed row or rows at a discharge station, means for discharging the articles thus positioned, and variable speed means for determining the operation of the positioning and discharging means in relation to the operations of the said ejecting and compression means.

18. In a machine of the class described, the combination with an article carrier, of means for ejecting successive rows of articles therefrom, a support upon which the articles are ejected, said support having a throat portion, movable shutters for said throat portion, means for actuating said shutters, means for positioning one or more rows upon the shutters, means for discharging through the throat portion the articles thus positioned, and variable speed means for de-

termining the operations of the positioning, discharging and shutter-actuating means in relation to the operation of the said ejecting means.

19. In a machine of the class described, the combination with an article carrier, of means for ejecting successive rows of articles therefrom, a support upon which the articles are ejected, said support having a throat portion, movable shutters for said throat portion, means for actuating said shutters, means for compressing one or more rows of articles upon the said support, means for positioning the compressed row or rows upon the shutters, means for discharging through the throat portion the articles thus positioned, and variable speed means for determining the operations of the positioning, discharging and the shutter-actuating means in relation to the operations of the said ejecting means and the compression means.

20. In a machine of the class described, the combination with an article carrier, of a plunger mechanism for ejecting successive rows of articles therefrom, a support upon which the articles are ejected, plunger mechanism for positioning one or more rows at a discharge station, plunger mechanism for discharging the articles thus positioned, and variable speed means for determining the operations of the positioning and discharging mechanisms in relation to the operation of the said ejecting mechanism.

21. In a machine of the class described, the combination with an article carrier, of plunger mechanism for ejecting successive rows of articles therefrom, a support upon which the articles are ejected, plunger mechanism for compressing one or more rows thus ejected, plunger mechanism for positioning the compressed row or rows at a discharge station, plunger mechanism for discharging the articles thus positioned, and variable speed means for determining the operations of the positioning and discharging mechanisms in relation to the operations of the said ejecting and compression mechanisms.

22. In a machine of the class described, the combination with an article carrier, of plunger mechanism for ejecting successive rows of articles therefrom, a support upon which the articles are ejected, said support having a throat portion, movable shutters for said throat portion, mechanism for actuating said shutters, plunger mechanism for positioning one or more rows upon the shutters, plunger mechanism for discharging through the throat portion the articles thus positioned, and variable speed means for determining the operations of the positioning, discharging and shutter-actuating mechanisms in relation to the operation of the said ejecting mechanisms.

23. In a machine of the class described, the combination with an article carrier, of plunger mechanism for ejecting successive rows of articles therefrom, a support upon which the articles are ejected, said support having a throat portion, movable shutters for said throat portion, mechanism for actuating said shutters, plunger mechanism for compressing one or more of the rows of articles upon said support, plunger mechanism for positioning the compressed row or rows upon the shutters, plunger mechanism for
- 5
10

discharging through the throat portion the articles thus positioned, and variable speed means for determining the operations of 15 the positioning, discharging and shutter-actuating mechanisms in relation to the operation of the said ejecting and compression mechanisms.

Signed at Barberton, in the county of 20 Summit and State of Ohio, this 1st day of Nov., A. D., 1916.

JOSEPH C. DONNELLY.
